UNITED STATES PATENT OFFICE.

SAMUEL RUBEN, OF NEW YORK, N. Y.

ELECTRICAL VACUUM-DISCHARGE TUBE.

Application filed January 17, 1924. Serial No. 686,852.

This invention relates to an electrical vacuum discharge tube; and more particularly, it relates to an X-ray tube in which conduction through the vacuous space is effected through control of the vapor pressure of an alkaline metal contained therewithin. Its chief object is to provide an efficient X-ray tube normally having constant discharge characteristics and externally controllable by varying the vapor pressure of an alkaline metal within the tube.

In the prior art there are two commonly used types of X-ray tubes, one depending upon the electron conduction between its cathode and anode elements, the other depending upon ionic discharge conduction therebetween by means of a gas or vapor supply. In the latter or ionic type, an electrical discharge between its cathode and anode is effected through the medium of a residual gas or vapor within the tube, and, on its absorption by the tube elements, is replenished through a gas or vapor liberated for vapor adjustment from a material combined with carbon dioxide or water vapor, by the application of heat. The adjustment is continued until the desired pressure condition for the electrical discharge is reestablished. This type is very unstable in operation and requires continual adjustment of its gas content, as its operation is dependent upon ionic bombardment of its cathode to effect a discharge of electrons to the anode. It requires a direct current from a high potential source.

Broadly, this invention consists of a vacuum tube evacuated to a pressure at which negligible positive ionization can occur, and containing an alkaline metal which, when heated, produces an increased vapor pressure which permits a current conduction between the electrodes, upon the application thereto of sufficient potential.

The invention comprises an ionic conducting tube, having normally constant pressure characteristics, the operation factor of which is variable to a degree not possessed by the ionic discharge tubes of the prior art. It consists of a highly evacuated tube having, in a chamber connecting with that containing the cathode and anode elements, an alkaline metal, such, for instance, as sodium, the vapor pressure of which at normal operating temperatures, is insufficient for practicable ionic conduction between the electrodes, but which is controllable by the application of

heat to the metal, the degree of ionic conduction being thus controllable at fixed potentials. At ordinary or room temperatures, the application of high potentials to the electrodes effects negligible ionic conduction between them; but, upon the application of heat to the alkaline metal an increase in its vapor pressure occurs, permitting sufficient electrical conduction between the electrodes.

The electron discharge in part is due to the photoelectric character of the alkaline metal vapor under the influence of short wave radiations from the anode and from secondary ionization of the vapor.

Any residual gas emitted from the tube elements is both chemically and physically absorbed by the alkaline metal vapor, which maintains a constant initial discharge characteristic for the tube. In this tube geometrical factors can be employed in the design of the cathode and anode elements, which permits self-rectification. Preferably the cathode is composed of a material having a very high thermal conductivity and melting point and is pointed at the discharge end. I have found hardened copper to make a very satisfactory cathode. The anode is of the type commonly used in tubes of this kind, that is, composed of a refractory material, such as tungsten, employed as the target, in close contact with a metal of high heat conductivity, such as copper. Oscillographic records of the operation of the tube indicate characteristics different from those of tubes of the prior art; the current flows between the electrodes only at the maximum values of the applied alternating current oscillations, which effects an increased efficiency in X-ray production, compared with that of the tubes of the prior art, all of which use the low amplitude values of the applied oscillations, which produce undesirable radiations of longer wave lengths.

The principle employed can best be explained in connection with a certain illustrative embodiment of the invention shown in the accompanying drawings, in which,

Fig. 1 shows an X-ray tube of this invention connected in an electrical circuit arranged for its operation. Fig. 2 illustrates in detail the various elements of the portion of the tube containing the alkaline metal.

Referring more particularly to Fig. 1, in the highly evacuated glass tube 3, 1 represents the pointed hardened copper cathode and 2, the copper anode having a tungsten

target 2_a, for, the electron bombardment, the anode being held in place by the metal ferrule 4, and having its lead at 8. At 5 is represented the chamber containing alkaline metal. The lead from the cathode is shown at 7 and at 6 is a metal plug for holding the tube in a socket. The various other elements in the electrical circuit are the alternating current generator 12, transformers 9 and 10, with their respective primaries and secondaries P and S, and P₁ and S₁, and variable resistance 11.

Referring more particularly to Fig. 2, 15 represents the heating wire wound about chamber 5, containing alkaline metal 16, heat insulated by a layer of asbestos 14, and an electrical insulating shell 13.

The operation of the tube is as follows: Alternating current of high potential as generated at 12, is applied to electrodes 1 and 2, through transformer 9. At normal temperatures there is negligible discharge between the electrodes due to positive ionization, until heat is applied by transformer 10, 25 and controlled by resistance 11, to the alkaline metal 16, when its vapor pressure is increased and through the ionic bombardment of the cathode, a stream of electrons discharges from the cathode to the target 2_a 30 from which the X rays are radiated.

The tube walls and the anode and connecting parts become highly heated by thermal radiation from the anode during the operation of the tube, resulting in the discharge 35 of alkaline metal vapor from the walls. The cathode chamber, though somewhat heated to obtain the increase of the vapor pressure of the alkaline metal, is the coolest part of the tube after being in operation.

40 The cathode, being pointed at its discharge end, allows more current to flow in one direction, due to which self rectification results.

What I claim is:

1. An X ray tube comprising a sealed 45 envelop, exhausted to a pressure at which at normal temperature no positive ionization can occur, and containing a cathode and an anode, said cathode composed of metal of high thermal conductivity, and a mass of alkaline metal, in combination with means 50 for establishing a potential between said cathode and anode, and means for applying heat independently to said alkaline metal.

55 2. An X ray tube comprising a sealed envelop, exhausted to a pressure at which at normal temperature substantially no positive ionization can occur, and containing a cathode and an anode and a mass of alkaline metal, said cathode composed of metal of

high thermal conductivity and pointed on 60 the part thereof facing said anode, in combination with means for establishing a potential between said cathode and anode, and means for applying heat independently to said alkaline metal to raise the vapor pressure of the tube and increase the ionic conduction between the electrodes. 65

3. An X ray tube comprising a sealed envelop evacuated to a pressure at which, at the normal vapor pressure therein, substantially no positive ionization can occur, 70 and containing cooperating electrodes and a mass of alkaline metal, and means for maintaining an ionic discharge between the electrodes at a potential, insufficient at normal vapor pressure in the tube to maintain an ionic discharge, comprising means independent of said discharge for heating the alkaline metal. 75

4. An X ray tube comprising a gas-tight 80 vessel evacuated to a pressure at which substantially no positive ionization can occur, and containing cooperating electrodes and a mass of alkaline metal and means for establishing a potential between said electrodes 85 and means for maintaining an electrical discharge between said electrodes at a given potential by controlling the vapor pressure within said tube by heating said alkaline metal by a source independent of said discharge. 90

5. An X ray tube comprising a gas-tight vessel evacuated to a pressure at which substantially no positive ionization can occur, 95 and containing cooperating electrodes and a mass of sodium, and means for establishing a potential between said electrodes, and means for maintaining an electrical discharge between said electrodes at a given potential by controlling the vapor pressure 100 within said tube by heating said sodium by a source independent of said discharge.

6. An X ray tube comprising a sealed envelop, exhausted to a pressure at which at normal temperatures, no positive ionization 105 can occur, and containing a cathode and an anode, said cathode being composed of a metal of high thermal conductivity, and a mass of alkaline metal, in combination with means for establishing a potential between 110 said electrodes, and means for raising the vapor pressure within the tube by applying heat to said alkaline metal, independent of a discharge between the electrodes.

Signed at New York, in the county of 115 New York and State of New York, this 12th day of January A. D. 1924.

SAMUEL RUBEN.
